Application March 12, 1953, Serial No. 341,921

6 Claims. (Cl. 229—19)

This invention relates to a shipping container for one or more elongated articles, which is well suited for receiving Venetian blinds and head bars and bottom bars therefor.

The container of the present invention is formed of two, open-ended, boxlike container parts, one of which is telescoped over the open end of the other. The container is particularly well suited for Venetian blinds of varying widths and for bundles of varying lengths of Venetian blind head bars and bottom bars, the same size container serving over a substantial range of sizes by varying the amount by which the outer container part is telescoped over the open end of the inner container part.

In the form shown of the present invention, the inner container part may be folded into boxlike form about the article or articles to be received, the container part being folded from a single sheet of paperboard which has previously been cut and scored to facilitate folding. It is unnecessary to glue, staple, or otherwise secure the inner container part, the outer container part serving to hold it in folded, boxlike form.

The outer container part, which is folded generally similarly to the inner container part, requires only a minimum amount of tape which serves to hold it against unfolding and also to secure it in telescoped relation to the inner container part so as to seal the container for shipping.

Among the objects of the present invention are to provide a strong and rigid paperboard container of variable length for reception of one or more elongated articles of varying length; to provide such a container that is easily folded, packed, and sealed; to provide such a container that is easily unsealed; to provide such a container that is economical and easy to manufacture; and to generally improve containers of the type described.

Further objects and objects relating to details and economies of manufacture and use will more definitely appear from the detailed description to follow.

My invention is clearly defined in the appended claims. In the claims, as well as in the description, parts are at times identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawings forming part of this specification, in which:

Fig. 1 is a somewhat diagrammatic plan view of the blank from which the inner container part is folded.

Fig. 2 is a somewhat diagrammatic plan view of the blank from which the outer container part is folded.

Fig. 3 is an isometric view showing the folding of the inner container.

Fig. 4 is an isometric view of the folded outer container.

Fig. 5 is an isometric view of the container during assembly.

2

Fig. 6 is an isometric view of the container after closing and sealing.

Fig. 7 is a cross section taken generally on the line 7—7 of Fig. 6, the central zone of the container being broken away for convenience of illustration.

Referring generally to the drawings, the container 11 of the present invention is formed of an inner, open-ended, boxlike container part 12 and an outer, open-ended, boxlike container part 14, the container part 14 being telescoped over the open end of the container part 12 to close the container and being sealed by industrial sealing tape 15 holding the two container parts in telescoped relation and also holding these parts against unfolding.

The inner container part is formed from a blank generally indicated in Fig. 1, the proportions of the various sections of this blank being varied according to dimensions of the article or articles to be packed. The container of the present invention is particularly well suited for elongated articles or for bundles of articles of uniform length, the article or the bundle having a generally rectangular cross section. The carton of the present invention has its greatest utility for packaging of articles of varying lengths, one size of carton serving for a wide range of lengths by varying the amount by which the outer container part 14 is telescoped over the inner container part 12, so as to make unnecessary the stocking of a wide range of sizes of containers.

Referring to Fig. 1, the blank for forming the inner container part 12 is formed of a single piece of paperboard or the like, preferably double-faced, corrugated paperboard. The blank is cut and scored as indicated to provide sides 16 and 17 adapted to extend along the major portion of the length of two opposite sides of the article to be packed and an end 19 of the container part adapted to extend across the end of the article to be packed. The sides 16 and 17 are separated from end 19 by score lines to facilitate folding, the score lines being indicated in the drawings by broken lines.

Side flaps 20, 20 and 21, 21 extend laterally from the sides 16 and 17, respectively, the side flaps being separated from the sides by score lines as indicated in broken lines to facilitate folding. The side flaps 20 and 21 preferably extend out from the sides 16 and 17, respectively, for a distance approximately equal to the space between the score lines separating the end 19 from the sides 16 and 17, which distance is approximately equal to the edge dimension of the article to be packed.

An end flap 22 extends from the end of each of the side flaps 20, 20 adjacent the end 19 of the container part, the end flaps 22, 22 being separated from the side flaps 20, 20 by score lines as indicated to facilitate folding.

The inner container part 12 is preferably folded about the article or articles to be packed, as indicated in Fig. 3. This is accomplished by laying the article or articles on the side 17 of the container part with one end of the article adjacent the score line separating this side of the container from the end 19. The side flaps 20, 20 are folded upwardly from the plane of the side 16 of the container part and the end flaps 22, 22 folded inwardly at right angles to the side flaps 20, 20. Then, the side 16 may be folded over through the position shown in Fig. 3 and against the exposed side of the article or articles, the end 19 overlying (lying against the outer surface of) the end flaps 22, 22 and the side flaps 20, 20 overlying the side flaps 21, 21.

The outer container part 14 is generally similar to the inner container part 12 and is folded into open, boxlike form in a generally similar manner. Referring to Fig. 2, the blank for the outer container part comprises two side portions 24 and 25 connected by an end portion 26, the side portions being separated from the end portion by

score lines, indicated by broken lines, to facilitate folding. The length of the side portions 24 and 25 may be about the same as the length of the side portions 16 and 17 but the width of these portions and of the end portion 26 is slightly greater in order to permit the folded outer container part to be telescoped over the inner container part.

Side flaps 27, 27 and 29, 29 project laterally from side portions 24 and 25, respectively, these side flaps being separated from the portions 24 and 25 by score lines as indicated and the side flaps preferably likewise being slightly larger in order to facilitate telescoping of the outer container part over the inner container part. End flaps 30, 30 project from the ends of the side flaps 27, 27 adjacent the end portion 26, these end flaps corresponding generally to the end flaps 22, 22 of the container part 12.

A marginal flap 31 extends from the side of each side flap 27 opposite to the end flap 30, these flaps being separated from the side flaps 27, 27 by a double score to facilitate bending these flaps back about the adjacent edge of the side flaps 29. Initially, the ends of the marginal flaps 31, 31 may lie generally along the line of the end of the side portion 24; but, after folding the container into boxlike form as indicated in Fig. 4, both side portions 24 and 25 will extend beyond the side flaps to facilitate sealing the carton, as will be explained. Four locking flaps 32 are formed from the outer corners of the side portions 24 and 25 as indicated in Fig. 2.

The outer container part 14 is first folded into boxlike form in generally the same manner as the inner container part 12. The side flaps 27, 27 are folded up from the plane of the side portion 24 and the end flaps 30, 30 folded inwardly to a position lying along the score line separating the side portion 24 and end portion 26. Then the side flaps 29, 29 are folded up from the plane of the side portion 25 and the side portion 25 folded up into parallel relation with the side portion 24, the side flaps 29, 29 being entered inside of the flaps 27, 27. Then, the marginal flaps 31, 31 are folded inward about the adjacent edge of the side flaps 29, 29. These flaps are held in folded position by folding the locking flaps 32 inwardly against the inner surface of the side portions 24 and 25 so as to overlie the ends of the marginal flaps 31, 31 (see Fig. 4).

The outer container part 14 may then be telescoped over the article or articles to be packed and the open end of the inner container part 11, the outer container part being telescoped until the end of the container formed by the end flaps 30, 30 and the end portion 26 rests against the end of the contained article.

As above described, the side portions 24 and 25 of the outer container part 14 project beyond the other two sides of the container part formed by the flaps 27, 27 and 29, 29. In sealing the container, industrial sealing tape 15, such as gummed paper or fiber-glass-reinforced cellophane tape, may be placed about the four corners of the container, portions of the entire width of the tape lying on the outer surface of the side flaps 20, 20 of the inner container part 12 and other portions of the entire width of the tape lying on the outside surface of the ends of side portions 24 and 25. The tape 15 may be a single length of tape extending about the circumference of the container or may be a separate piece at each corner, as indicated in Fig. 6. The tape 15 not only serves to hold the inner and outer container parts 12 and 14 in telescoped relation, but additionally serves to hold the side portions 24 and 25 of the outer container part from separating.

Since the outer container part 14 is a snug fit over the inner container part 12, the inner container part holds the locking flaps 32 and the marginal flaps 31, 31 against unfolding. The marginal flaps 31, 31 and locking flaps 32 serve as a slightly resilient cushion between the inner and outer container parts 12 and 14 and assure a tight fit between these parts.

Substantially all portions of the sealing tape 15 are in contact with either the inner or outer container parts,

there being very little bridging of the tape between the inner and outer container parts. In this connection, the reduced width of the extremities of the side portions 24 and 25 of the outer container part 14, caused by folding inwardly the locking flaps 32, substantially reduces the bridging of the sealing tape 15 and contributes to a much stronger and superior sealing of the container.

I claim:

1. A shipping container for one or more elongated articles of generally rectangular cross section, said container comprising: an inner, open-ended, boxlike container part folded from a single piece of paperboard and adapted to extend along two opposite sides and across an end of the article to form two sides and an end, side flaps extending laterally from both sides of the container part and adapted to be folded over the other two sides of the article, the side flaps from opposite sides of the container part lying in telescoped relation, and an end flap extending from the end of each of the outside side flaps adjacent the end of the container part and lying along the inside of said end; an outer, open-ended, boxlike container part telescoped over the open end of the inner container part, said outer container part being folded from paperboard, the outer container part having a similar structure to the above-recited structure of the inner container part, being folded in the same manner as the inner container part, and additionally including a marginal flap extending from the end of each outside side flap adjacent the open end of said outer container and folded back about the adjacent edge of the inner side flap and flaps folded inwardly from the sides of the outer container and lying across the ends of said marginal flaps, the sides of said outer container extending beyond the folded-back flaps; and sealing tape received partly on the outside side flaps of the inner container part and partly on the extended portion of the sides of the outer container part.

2. A shipping container for one or more elongated articles of generally rectangular cross section, said container comprising: an inner, open-ended, boxlike container part folded from a single piece of paperboard and adapted to extend along two opposite sides and across an end of the article to form two sides and an end, side flaps extending laterally from both sides of the container part and adapted to be folded over the other two sides of the article, the side flaps from opposite sides of the container part lying in telescoped relation, and an end flap extending from the end of each of the outside side flaps adjacent the end of the container part and lying along the inside of said end; an outer, open-ended, boxlike container part telescoped over the open end of the inner container part, said outer container part being folded from paperboard, the outer container part having a similar structure to the above-recited structure of the inner container part, being folded in the same manner as the inner container part, and additionally including a flap extending from the end of each outside side flap adjacent the open end of said outer container and folded back about the adjacent edge of the inner side flap and against the inner face thereof; and sealing tape received partly on the outer container part and partly on the exposed portion of the inner container part adjacent the outer container part.

3. A shipping container for one or more elongated articles of generally rectangular cross section, said container comprising: an inner, open-ended, boxlike container part folded from a single piece of paperboard and adapted to extend along two opposite sides and across an end of the article to form two sides and an end, side flaps extending laterally from both sides of the container part and adapted to be folded over the other two sides of the article, the side flaps from opposite sides of the container part lying in telescoped relation, and an end flap extending from the end of each of the outside side

flaps adjacent the end of the container part and lying along the inside of said end; an outer, open-ended, box-like container part telescoped over the open end of the inner container part, said outer container part being folded from paperboard, the outer container part having a similar structure to the above-recited structure of the inner container part, being folded in the same manner as the inner container part, and additionally including a flap extending from the end of each outside side flap adjacent the open end of said outer container and folded back about the adjacent edge of the inner side flap and against the inner face thereof, the sides of said outer container extending beyond the folded-back flaps; and sealing tape received partly on the outside side flaps of the inner container part and partly on the extended portion of the sides of the outer container part.

4. A shipping container for one or more elongated articles of generally rectangular cross section, said container comprising: an inner, open-ended, boxlike, four-sided container part; an outer, open-ended, boxlike, four-sided container part telescoped over the open end of the inner container part, marginal flaps on two opposite sides of the open end of the outer container part being folded inwardly and back upon themselves, the other two sides of said outer container extending beyond the folded-back flaps; and sealing tape received partly on the outside of the inner container part and partly on the extended portion of the sides of the outer container part.

5. A shipping container for one or more elongated articles of generally rectangular cross section, said container comprising: an inner, open-ended, boxlike container part; an outer, open-ended, boxlike container part telescoped over the open end of the inner container part, marginal flaps on two opposite sides of the open end of

the outer container part being folded inwardly and back upon themselves and locking flaps folded inwardly from the other two sides of said container part and lying across the ends of said marginal flaps, the other two sides of said outer container part extending beyond the folded-back flaps; and sealing tape received partly on the outside of the inner container part and partly on the extended portion of the sides of the outer container part.

6. A shipping container for one or more elongated articles of generally rectangular cross section, said container comprising: an inner, open-ended, boxlike, four-sided container part; an outer, open-ended, boxlike, four-sided container part telescoped over the open end of the inner container part; the central portions of two opposite sides of said outer container part extending beyond the remaining portions of said sides and all of the other two sides thereof; and sealing tape received partly on the outside of the inner container part and partly on the extended portion of the sides of the outer container part.
